(57) **CLAIM**

The ornamental design for a starred patrol cap, as shown and described.

DESCRIPTION

FIG. 1 is a top perspective view of a starred patrol cap, showing a first embodiment of my new design;

FIG. 2 is a bottom perspective view of FIG. 1;

FIG. 3 is a front elevational view of FIG. 1;

FIG. 4 is a rear elevational view of FIG. 1;

FIG. 5 is a right-side elevational view of FIG. 1, the left-side elevational view being a mirror image thereof;

FIG. 6 is a top plan view of FIG. 1;

FIG. 7 is a bottom plan view of FIG. 1;

FIG. 8 is a top perspective view of a second embodiment thereof;

FIG. 9 is a bottom perspective view of FIG. 8;

FIG. 10 is a front elevational view of FIG. 8;

FIG. 11 is a rear elevational view of FIG. 8;

FIG. 12 is a right-side elevational view of FIG. 8, the left-side elevational view being a mirror image thereof;

FIG. 13 is a top plan view of FIG. 8; and,

FIG. 14 is a bottom plan view of FIG. 8.

The broken line outlines of the stars in FIGS. 1, 3, 5, 8, 10, and 12 depict portions of the starred patrol cap that form no part of the claimed design. The remaining broken lines represent stitching, and are part of the claimed design.
